UNITED STATES PATENT OFFICE

VLADIMIR J. POLYDOROFF, OF CHICAGO, ILLINOIS, ASSIGNOR TO JOHNSON LABORATORIES, INCORPORATED, OF CHICAGO, ILLINOIS, A CORPORATION OF ILLINOIS

RADIO CIRCUITS

Application filed July 6, 1926. Serial No. 120,733.

The invention relates to radio-frequency circuits, and provides means for eliminating the undesirable feed-back effects through the audions of such circuits, and for apportioning the energies of output circuits.

The invention will be better understood if reference be made to the accompanying drawings, in which—

Figure 1, is a schematic drawing of the circuit arrangement of this invention, and

Figure 2, is a second view of the same circuit, arranged in a form to clearly show the balanced circuit of this invention.

Figure 1, shows a new arrangement, where the undesirable capacity effects are eliminated, providing that the two audions circuits shown have substantially the same internal capacity or means to make their capacities equal. The incoming voltage vi is applied to the winding 1 of a transformer whose secondary winding 2 with condenser 3 forms grid circuits of audions 4 and 5.

The grids of both audions are bridged by a non-inductive resistance 6, the middle part of which resistance is brought to a biasing battery 7 in order to keep the grid potential negative with respect to the filament and prevent distorting effects.

The plates of both tubes may be connected to a common plate battery 8 through two separate and non-inductively related windings 9 and 10, wound in two transformers whose secondaries, 11 and 12, supply out-put voltages Vo 1 and Vo 2 to succeeding audions or pair of audions in the radio receiving system.

In Figure 2, the same arrangement is schematically represented in the convenient form of a Wheatstone bridge. Winding 1 related to winding 2 and connected to points 15 and 16 of the bridge, and distributed to four branches 17, 18, 19 and 20, the non-inductive resistances 6, of branches 17 and 18, being many times greater than the resistances of branches 19 and 20. In the branches 19 and 20, are shown two audions 4 and 5, and their respective plate windings, 9 and 10. Out-put voltage is applied to two separate and non-inductively related windings 11 and 12 in which, by varying the re-

sistance of the branches 17, 18, desired differences of potential may be established irrespective of the balancing of the audions. The arms of the bridge 17, 18, 19 and 20 may be so chosen that there will be no potential difference between points 15 and 16 when an E. M. F. is applied to windings 9 and 10 or windings 11 and 12, thus eliminating the undesirable feed-back effects through the audions.

If branches 19 and 20 are unbalanced, compensating adjustment may be made in branches 17 and 18, by the adjustable connection of the battery 7.

A single stage of radio frequency amplification may be connected to my system in which case windings 11 and 12 will be connected in series aiding (Vo 1 and Vo 2) and will be the in-put circuit to the succeeding stage of radio frequency amplification or detector.

The action of the circuit will be understood from Figure 2.

Incoming radio frequency signal is applied to winding 1 as vi and is inductively transferred to winding 2 which is in the diagonal 22 of the bridge. Winding 2 if associated with condenser 3 forms an oscillatory circuit 2 and 3, responding to the same frequency as the incoming signal. The impedance of this circuit 2 and 3, when tuned to resonance, is very low as compared with resistances and impedances of branches 17, 18, 19, 20 and therefore, the bridge at its point 15 and 16 acts as a voltage amplifying device, the voltage variations being applied on the grids or tubes 4 and 5 simultaneously and of opposite sign. However, resistances of 17 and 18, permit battery 7, to maintain grids of tubes at negative potential.

Amplified voltages of same frequencies are produced by plate circuits. The plate currents of both tubes have their useful paths through their respective windings 9 and 10 and battery 8 back to filament circuit in diagonal 21. Part of this plate current leaks through capacities of tubes 4 and 5 back into input circuit 2 and 3 and tends to produce undesirable oscillations in the circuit 2 and 3 and in winding 1. When the impedances

due to the capacities of the tubes are substantially equal the feed back current affects points 15 and 16 equally and in opposite direction so that undesirable oscillations will be 5 eliminated. When the said impedances are not equal the balance of diagonal 22 can be obtained by adjusting non-inductive resistance 6, constituting branches 17 and 18. These resistances may be chosen near to the 10 order of said impedances of tube capacity at high frequency.

The same balancing effects will be attained if feed back currents occur in winding 11 and 12 and the same adjustments in the 15 bridge are made.

Under some conditions, it may be desirable to so vary the adjustable connection of the battery 7 that the branches 19 and 20 are unbalanced and that, consequently, the windings 20 9 and 10 and 11 and 12 are unequally affected by incoming signals.

The system as described may be used for 25 radio frequency amplification. Tests show that many stages of cascade amplification can be successfully controlled without objectionable oscillations, and that it is practical to place double-stage amplification between ordinary single stages.

Having thus described my invention, I 30 claim:

1. In a radio-frequency apparatus, means 35 for balancing the inter-electrode capacities of two audions consisting of two audions disposed in two branches of a Wheatstone bridge, two non-inductively related plate windings also disposed in said branches of said Wheatstone bridge, adjustable impedances disposed in the other two branches of said Wheatstone bridge, an input circuit constituting one diagonal of said bridge, and sources of current and filaments of said audions constituting the other diagonal of said bridge.

2. In a radio-frequency apparatus, means 45 for balancing the inter-electrode capacities of two audions consisting of two audions disposed in two branches of a Wheatstone bridge, two non-inductively related plate windings also disposed in said branches of said Wheatstone bridge, adjustable impedances disposed in the other two branches of said Wheatstone bridge, an input circuit constituting one diagonal of said bridge, and output windings inductively related to said plate windings to apportion the amplified output energy to two independent channels by adjustment of said impedances.

3. An amplifying system including two 60 audions having their plate windings non-inductively related and provided with a common plate-potential source, the grids of said audions being connected with opposite ends of a parallel resonant input circuit, and an 65 impedance connected across said input circuit

controlled by an adjustable tap connected with a biasing source.

4. A system, including the four arms and the diagonals of a Wheatstone bridge, an input circuit of which one diagonal of said bridge is an element, two audions and their plate windings arranged in adjacent arms of said bridge, and the other two arms of said bridge constituting variable serial impedances connected across said input circuit, a 70 biasing source of energy disposed in the other diagonal of said bridge, and two out-put windings inductively related to said plate windings.

In testimony whereof I affix my signature. 80
